COMBINED CONTAINERS AND CLOSURE CAPS THEREFOR

Sigmund E. Edelstone and Albert E. Neely, Chicago,
Ill., assignors to Dupli-Color Products Company, Inc.,
Chicago, Ill., a corporation of Illinois

Application November 26, 1958, Serial No. 53,542

Term of patent 14 years

(Cl. D58—8)

Figure 1 is a side elevational view of combined containers and closure caps therefor shown in closed position and showing our new design;

We claim:

The ornamental design for combined containers and closure caps therefor, substantially as shown.
